PLASTIC HINGE CONSTRUCTION FOR
BOXES AND THE LIKE

Finn H. Magnus, Essex Fells, N. J., assignor to
Magnus Research, Incorporated, a corporation
of New Jersey

Application September 12, 1947, Serial No. 773,707

1 Claim. (Cl. 220—31)

1

The invention relates particularly to improved hinge constructions for boxes or receptacles and the like formed of plastic material.

A prime object of the present invention is to provide a box or receptacle of this class with a body section and a cover section having hinge members provided with improved means for maintaining the sections in hinged relation.

Another object is to provide a box or receptacle of this kind having a body section and a cover section with aligned cooperating hinge members formed integrally therewith and held in hinged relation by parts disposed between said hinged members and formed integrally with said body and cover sections.

Still another object is to provide a box or receptacle with improved means for holding the cover section of the box in open or closed position.

Other objects of the invention are to provide a hinge construction that is simple in construction, economical to manufacture and possesses the strength and rigidity necessary for heavy or moderately heavy duty.

The invention will be better understood from the description thereof to follow taken in connection with the accompanying drawing in which—

Figure 1 is a perspective view of a box embodying the invention.

Figure 2 is a fragmentary side view showing the body section and cover section of the box disassembled.

Figure 3 is a rear view showing the body section and cover section of the box disassembled.

Figure 4 is an enlarged fragmentary vertical sectional view taken on the plane of the line 4—4 of Figure 1.

Figure 5 is a similar view showing the cover in open position.

Figure 6 is an enlarged fragmentary horizontal sectional view taken on the plane of the line 6—6 of Figure 4.

Referring to the drawing, the improved hinge construction is illustrated as embodied in a box or receptacle formed of plastic material, such as the material sold under the trade name "Bakelite" but it may be made of any other suitable material. The box is shown substantially rectangular in shape having a lower or body section 1 and an upper or cover section 2. The rear wall 3 of the cover section is formed adjacent each of its ends with an integral hinge leaf or member 4, the body portion of which tapers downwardly and outwardly of the rear wall and terminates in a semi-cylindrical or beaded portion

or knuckle 5. The knuckle extends slightly below the lower edge 6 of the cover section as shown in Figures 1 and 2. A hinge pin 7 is formed integrally with the knuckles and forms a connection between the two hinge members, the pin being aligned axially with the knuckles 5 and spaced outwardly of the rear walls of the box sections. The cover section is formed with a slotted portion 8, along its lower edge, about midway its ends.

The lower or body section 1 is formed with similar hinge leaves or members 9 spaced on its rear wall 10, but each member tapers upwardly and outwardly and terminates in a semi-circular groove 11 adjacent the upper edge 10' of said body section as best shown in Figure 2. When the sections of the box are assembled as shown in Figure 1, the knuckles 5 seat in the grooves 11.

The means for retaining the box sections in assembled hinge relation includes a tongue member 12 integral with the upper edge 10' of the body section and extending upwardly therefrom and outwardly thereof forming a flange portion 13 at its upper end which projects over the hinge pin 7. The slotted portion 8 of the cover section permits this arrangement. The hinge pin is formed at its center for substantially one-half its circumference with an enlargement 14 extending the length of the flange 13 and having a flat face 15 along one side and having another flat face 16 extending at right angles to the face 15.

The sections of the box are assembled or connected by moving them into registering relation by forcing the enlargement of the hinge pin underneath the flange 13 whereby due to the resiliency of the plastic material the flange 13 will be sufficiently flexed upwardly and the hinge pin 7 will be sufficiently bowed or bent downwardly to permit the knuckles 5 to snap into their seats in the grooves 11.

By reason of this construction, when the cover section is in closed position as shown in Figure 4, the flange 13 is in engagement with the flat surface 16 of the hinge pin and because said flat surface is offset from the axis of the hinge pin a continuous pressure is exerted by the flange through the hinge pin on the sections of the box thereby holding the cover section firmly in closed position.

When moving the cover section from the closed position of Figure 4 to the open position of Figure 5, the hinge pin with its enlargement is rotated, the enlargement serving as a pivot point, so that the flat surface 16 is moved away from

and the flat surface 15 is moved into engagement with the flange 13, the cover section moving freely in an arc 90 degrees. During this opening movement, the tension on the hinge pin is increased as the shoulder 17 of the enlargement slides across the flange 13. When in open position, the flange 13 is continuously pressing downwardly on the flat surface 15 of the hinge pin because of the off center position of said flat surface thereby holding the cover section in open position.

A lug 18 is integrally formed on the surface of the hinge pin opposite to and centrally of the enlargement, which lug is adapted to engage the rear wall 10 of the body section 1 for limiting the 15 opening movement of the cover section as shown in Figure 5.

Changes in details of construction may be made without departing from the scope or principle of the invention.

What I claim is:

In a plastic box having a body section and a movable cover section, a hinge construction comprising spaced hinge members on the body section formed integrally therewith, spaced hinge members on the cover section formed integrally therewith and each aligned with one of the hinge members on the body section, said aligned hinge members having adjacent opposed coacting surfaces, a hinge pin formed integrally with and ex- 30

tending between said hinged members on said cover section, said pin being formed with an enlargement having flat face portions disposed at an angle to each other and offset from the axis of the pin, and a tongue member formed integrally with the body section between the corresponding hinge members and projecting vertically upward above and horizontally outwardly from said body section and adapted to coact with said face portions for retaining the sections in hinged relation and for holding the cover section in either a closed position or an open position, at least one of said tongue and said pin being resilient.
